TARGET ELECTRODES FOR USE IN TELEVISION PICK-UP TUBE OR THE LIKE

George Stanley Percival Freeman, Chiswick, London, England, assignor to Cinema-Television Limited, London, England, a British company

Application October 22, 1949, Serial No. 122,925

Claims priority, application Great Britain
November 22, 1948

2 Claims. (Cl. 313—326)

This invention relates to improvements in or relating to target electrodes for use in television pick-up tubes or the like and is more particularly concerned with such target electrodes of the double-sided type.

It has previously been proposed to construct a target electrode, for use in a television pick-up tube, which comprises a thin metal film in contact with one face of a thin layer of insulating material. In the operation of a tube comprising such a target electrode, primary electrons from a photosensitive cathode penetrate the metal film and release secondary electrons in the insulating material which are accelerated away from the exposed face thereof. With such a construction, it is difficult to prevent primary electrons reaching the metal layer from passing through both the metal and insulating layers; such penetrating primary electrons, in conjunction with the released secondaries, have a deleterious effect on the image signal when the insulating face of the target is scanned with a low-velocity electron beam and the signal is derived from the return beam. In another similar arrangement, a thin metal film is juxtaposed to one face of a thin glass layer; in this arrangement also there is the possibility that primary electrons incident on the metal film may pass completely through the target electrode and appear at the exposed glass face where the secondary electrons are liberated.

It is a primary object of the present invention to provide an improved double-sided target electrode, for use in a television pick-up tube or the like, which provides efficient image conversion while preventing primary photoelectrons from entering the scanning section of the tube.

According to the invention there is provided a target electrode, for use in a television pick-up tube or the like, comprising the combination of a thin metallic layer, a thin semi-conducting layer and a thin insulating layer, capable of emitting secondary electrons, interposed between the metallic and semi-conducting layers.

The present invention avoids the difficulty hereinbefore mentioned by virtue of the fact that electron velocities within the target electrode are reduced so that it is impossible for primary electrons from the photo-sensitive cathode to appear at the face of the target electrode which is scanned with the electron beam, although secondary emission is caused at an intermediate interface of the target electrode.

The features of the present invention which are believed to be novel are set forth with particularity in the appended claims. The invention, together with further objects and advantages thereof, may best be understood, however, by reference to the following description taken in connection with the accompanying drawing in which:

Figure 1 is a sectional view, partly schematic, of a television pickup tube embodying a target electrode constructed in accordance with the present invention, and

Figure 2 is a sectional view of another embodiment of the invention.

With reference to Figure 1, a television pickup tube comprises a continuous light-transparent photo-cathode

2

10 formed on the inside of the window 11 of an evacuated envelope 12. A target structure 13 is disposed in parallel relation with the photo-cathode 10 at a distance, for example, of about three millimeters. The target electrode 5 13 comprises a very thin electron-permeable metallic film 14 and a thin plate 15 of semi-conducting material, constructed of glass for example, of the type used in a conventional image orthicon. A thin layer 16 of insulating secondary electron emitting material is interposed between metallic film 14 and semi-conducting plate 15; preferably, insulating layer 16 is affixed to metallic film 14, as for example, by depositing film 14 on layer 16 in a manner well known in the art. Metallic film 14 may conveniently be made of aluminum, and insulating layer 16 may be constructed of aluminum oxide.

On the other side of the target electrode 13 is disposed an electron gun 17, which may be of conventional construction, and an electron multiplier system 18 is arranged to intercept the return beam. A decelerating system 19, which may comprise a series of annular metal rings operated at progressively higher potentials in a direction away from electron gun 17, is provided, the purpose of which will be hereinafter described. Scanning coils 20 are provided for deflecting the cathode-ray beam 25 to cause it to scan semi-conducting plate 15, and a long solenoid 21 surrounds the entire tube envelope 12 to provide a long axial magnetic field. Further electrodes 22, 23, and 24 are provided to control the cathode-ray beam; these electrodes may conveniently comprise conductive coatings on the internal walls of the tube envelope 12.

All of the electrodes may be supported within envelope 12 by conventional means well known in the art.

In operation, light from an image 25 is focussed on photo-cathode 10 by means of a lens 26, and primary electrons emitted from the photo-cathode 10 penetrate metallic film 14 and come to rest in the insulating layer 16 just short of the surface thereof distant from the metallic film 14, thus releasing secondary electrons and imparting a local negative charge to the semi-conducting plate 15. Thus, a "white" picture point produces a negative charge on the scanned face of the semi-conducting plate 15, while a "black" picture point produces no change of potential. With this arrangement, it is impossible for photoelectrons of released secondary electrons to penetrate through the semi-conducting plate into the evacuated space beyond.

The scanning of the target electrode is performed in a manner similar to the scanning in an orthicon or image orthicon type tube, but instead of the beam being decelerated to zero volts velocity, it is allowed to strike the target with, for example, 20-50 volts velocity, thus releasing more than one secondary electron per primary, and so restoring the target to an equilibrium potential near that of the final anode. The fact that the beam does not come to zero velocity improves the focus and also reduces the tendency for the beam to defocus at regions of high negative charge corresponding to high lights in the picture.

Since the envelope of the tube is surrounded by a long solenoid providing an axial magnetic field, the secondaries released by the scanning beam are substantially prevented from returning as a rain of secondaries to the target, and consequently the tilt and bend signals are of negligible proportions, if they are present at all. These secondaries, therefore, return to the gun end of the tube where they enter the electron multiplier 18.

If the tube receives an excess of light on the photo-cathode, the target may travel so negative in potential that the picture disappears because of the inability of the scanning beam to reach it, but the range of tolerance is very much greater in a device constructed in accordance with the invention than in the orthicon for instance, since

the permissible average potential change of the target is greater. The remedy for such a disappearance of the picture is either to apply a negative pulse to the gun cathode, or to apply a positive pulse to the thin metal film on the glass target.

To facilitate an understanding of the operation of the device, let it be assumed that point 27 of the image 25 is a "black" picture point, and point 28 is a "white" picture point. When the image 25 is illuminated, a local negative charge is imparted to the point 29 on semi-conducting plate 15 corresponding to point 28 of the image, and point 30 of the semi-conducting plate 15, corresponding to point 27 of image 25, is unchanged in potential. Primary electrons from electron gun 17 scanning points 29 and 30 release secondary electrons from the surface of semi-conducting plate 15; however, secondary electrons released from point 29 are accelerated to a greater velocity than those released from point 30. By adjusting the potentials applied to decelerating system 19, those secondary electrons released from "black" picture points may be prevented from reaching electron multiplier 18, and are returned to a collecting electrode 31. On the other hand, secondary electrons released from a "white" picture point, being of higher velocity, penetrate the decelerating field and enter electron multiplier 18. The electron multiplier may be of conventional construction, and a load impedance (not shown) may be coupled to the output electrode of the electron multiplier to develop an output signal.

Instead of deriving the picture signals from the return beam by way of the multiplier 18, the tube can be operated by drawing the picture signals capacitatively from the metal film 14 on the glass target, using this as a signal plate, though the capacity to earth via the photo-cathode may be rather high.

In the preferred embodiment, an aluminum pellicle 14 is held parallel and in very close proximity to a very thin glass plate 15. The face of the aluminum nearest the glass plate 15 is coated with a layer 16 of material having a high secondary emission coefficient.

The aluminum pellicle faces the photo-cathode, and the photoelectrons, travelling at high velocity, penetrate the aluminum film and are halted at the boundary of the high secondary emitting coating, thus releasing a copious supply of secondaries. These strike the glass plate, which is about .0002" distant from the secondary emitting coating so that the secondaries do not spread appreciably in travelling to the glass plate. Thus a negative charge appears on the glass target where a light pattern exists on the photo-cathode.

In another embodiment, illustrated in Figure 2, a glass plate 40 is coated on one side with a cellular amorphous layer 41 of aluminum oxide by known methods, and an aluminum film 42 is produced on this oxide layer as for example by methods similar to those used in producing a metal backing for a fluorescent screen. The term "amorphous" as used in connection with the aluminum oxide is used in its technical correct meaning of having no crystalline structure, and not in the sense of signifying merely an aggregate of finely divided crystalline particles.

This enables the glass plate to support the aluminum, but there is a loss in efficiency because the interstitial spaces in the cellular aluminum oxide amounts to only 40-50% of the covered area. Hence about half the photoelectrons are prevented from contributing signal and so this form of target is not substantially better in this re-

spect than the target structure used in the conventional image orthicon.

A target electrode constructed in accordance with the present invention has the following advantages as compared with the type of target electrode used in the conventional image orthicon pickup tube.

(1) The full photo-current is utilized and there is not a 50% loss due to the opaque grid wires in the conventional image orthicon target. (The Figure 2 embodiment does not have this advantage for the reason stated.)

(2) The mechanism of releasing secondary electrons by halting primary electrons in the surface boundary is very efficient and so high multiplication factors may be obtained.

(3) Since the glass target is in close proximity to the secondary emitting surface, a volt or two potential difference serves to saturate secondary electron emission and so prevent the "white after black" effects noticeable in the image orthicon at high light levels. Hence the contrast range is greater and there is less spurious shading due to redistribution of electrons over the target at high lighting than in the image orthicon.

The main disadvantage of the present invention is that there is less automatic control of the glass target potential relative to the capacitative electrode, and it may prove possible to drive the target so negative that the scanning beam cannot reach it. However, this is not a serious drawback since, if such a condition arises, the fact that the glass target is driven negative with respect to the aluminum layer tends to bias off the secondary emission caused by the photoelectrons and so helps the scanning mechanism to resume operation efficiently.

While particular embodiments of the present invention have been shown and described, it is apparent that various changes and modifications may be made, and it is therefore contemplated in the appended claims to cover all such changes and modifications as fall within the true spirit and scope of the invention.

I claim:

1. A target electrode for a picture-converting device comprising: a thin electron-permeable aluminum film; a thin semi-conducting glass plate supported parallel and in close proximity to said film; and a thin layer of insulating secondary-electron-emitting material spaced from said plate and affixed to the surface of said film facing said plate.
2. A target electrode for a picture-converting device comprising: a thin metallic film; a thin plate of semi-conducting material; and a thin layer of insulating secondary-electron-emitting material affixed to said film and spaced from said plate, the spacing between said layer and said plate being of the order of .0002 inch.
